UNITED STATES PATENT OFFICE

2,415,903

BRIDLE

George W. Norris, Jasper, Ala.

Application December 29, 1945, Serial No. 638,196

1 Claim. (Cl. 54—6)

1

This invention relates to a bridle and more particularly to the cheek straps of a bridle, it being one object of the invention to provide a bridle with cheek straps provided with buckles so formed and so mounted that when the cheek straps are in place, straps may be very easily engaged through the buckles and the cheek straps held in place without being subjected to wear which would be liable to weaken them.

Another object of the invention is to provide the cheek straps with buckles through which looped portions of the cheek straps pass, inner end bars of the buckle about which the loops engage being provided with sleeves for eliminating frictional wear upon the loops and the bills for the buckles being mounted at their outer ends and extending toward inner ends of the buckles for passing through openings in straps which are passed through the buckles. Due to this arrangement, the buckles are carried by upper and lower loops of the cheek straps instead of by other portions of the bridle and pull exerted upon the bills will tend to hold them close against the buckles and prevent them from accidentally moving to a releasing position.

Another object of the invention is to provide a bridle with cheek straps having inner and outer portions between which fillers carrying blinkers are mounted, the fillers terminating in spaced relation to loop-forming folds of the strips or straps from which the cheek straps are formed, and thus providing the cheek straps with loops which engage through inner ends of the buckle and so mount them that they cannot become detached from the cheek straps.

Another object of the invention is to provide a bridle with cheek straps having buckles so applied to them that portions of the cheek straps which engage through the buckle need not be formed with openings to receive bills of the buckles.

The invention is illustrated in the accompanying drawing, wherein:

Figure 1 is a perspective view showing a bridle having cheek straps of the improved construction in use.

Figure 2 is a sectional view taken longitudinally through a cheek strap of the improved construction.

Figure 3 is a fragmentary view showing the upper buckle and the manner in which it is mounted.

The bridle of which the improved cheek straps form portions has a head band 1 having its end portions secured across a strap which forms the brow-band 2 and the throat latch or strap 3.

2

The head band has its end portions 4 extending downwardly or forwardly from the strap forming the brow-band and the throat strap for engagement with buckles 5 at upper ends of the cheek straps 6.

The cheek straps 6 are of duplicate construction and each is formed from a strip of leather or other suitable material which has its upper portion folded outwardly and downwardly to provide inner and outer portions 7 and 8 joined by a loop 9 which passes through the upper buckle. The lower end portion of the outer portion 8 is folded inwardly and upwardly to form a lower loop 10 and this upwardly turned end of the outer portion is firmly secured by stitches 11 which pass through the inner and outer portions and also through a filler 12. The filler 12 is of double thickness and is firmly held in place between the inner and outer portions 7 and 8 and has its ends spaced from the folds forming the loops 9 and 10. It will thus be seen that the upper buckle 5 cannot become detached from the loop 9 which passes through it, and also that the lower buckle 13 cannot become detached from the lower loop 10 which passes through it. The lower portion of the strip from which each cheek strap is formed is of sufficient length to allow it to be passed through a ring 14 of a bit 15 and then folded outwardly and upwardly to provide a portion 16 which passes through the lower buckle 13. The two buckles are of duplicate construction and each is provided with a sleeve 17 which fits loosely about the cross-bar at the inner end of the buckle. The loops 9 and 10 engage about the sleeve 17 and from an inspection of Figure 2, it will be readily seen that the sleeve will prevent frictional wear upon the loops which would be liable to weaken them. The bill 18 of each buckle is pivotally mounted about the cross-bar at the outer end of the buckle and when the straps 4 and 16 are passed through the buckle and the bills passed through the openings 4' and 16', they will extend inwardly through the straps and since the extremities of the straps are passed through rings 19 and 20 carried by the upper and lower loops, the bills will be held against outward swinging movement and cannot swing outwardly to a position in which they can slip outwardly through the openings 4' and 16'. The pull exerted upon these straps will be applied to the bills close to their eyes 18' through which the outer end bars of the buckles pass and this will also urge the bills inwardly toward the outer portions 8 of the cheek straps. In view of the fact that the bills are carried by cross-bars at outer

ends of the buckles, it is not necessary to form slots in the loops 9 and 10 to accommodate the bills. Therefore, the loops are not weakened, and in addition, it is only necessary to apply one sleeve about each buckle instead of applying two sleeves, one at each side of the bill, and this will reduce the cost of manufacture. The fillers 12 may carry blinkers 21 or the blinkers may be omitted according to the type of bridle desired.

It is thought that persons skilled in the art to which the invention relates will be able to obtain a clear understanding of the invention after considering the description in connection with the drawing. Therefore, a more lengthy description is regarded as unnecessary.

Minor changes in the shape, size and arrangement of details coming within the field of invention claimed may be resorted to in actual practice if desired.

Having thus described the invention, what is claimed is:

In a bridle, cheek straps each comprising a strip having its upper portion folded outwardly

and downwardly to form inner and outer portions and having the lower end of its portions folded inwardly and upwardly and secured to said inner portion, a filler between the inner and outer portions and having its ends spaced from ends of the said outer portion, the folds at ends of the said outer portion forming upper and lower loops for the cheek strap, buckles through which said loops pass having loose sleeves about their inner ends about which the loops engage, and bills for said buckles.
